UNITED STATES PATENT OFFICE.

TOM WILSON, OF CHICAGO, ILLINOIS.

DRUM.

1,293,599.

Specification of Letters Patent.

Patented Feb. 4, 1919.

Application filed January 17, 1917. Serial No. 142,945.

To all whom it may concern:

Be it known that I, Tom Wilson, a citizen of the United States, residing at Chicago, in the county of Cook and State of Illinois, have invented certain new and useful Improvements in Drums, of which the following is a specification.

This invention relates to drums, and particularly to improvements in the means for adjusting the tension of the heads of drums. The invention is of particular value in connection with snare drums, for instance, in which it is desirable to prevent too great a tension in the snare head. In certain forms of drums now in use the opposite heads of the drum are adjusted simultaneously by the operation of a single adjusting means instead of adjusting the heads of the drum separately as was the common prior practice. Although it is a great advantage to be able to adjust the heads of a drum simultaneously by adjusting means, located preferably at one side of the drum, it will be seen that the operation of the adjusting means on the two heads of the drum simultaneously ordinarily tends to produce a greater tension in the snare head than in the beater head because the snare head is usually formed of thinner material and stretches more readily under the influence of the adjusting means. In order to secure the best operation of the drum it is desirable that the tension of the snare head be not greater than or perhaps slightly less than the tension of the beater head. It is therefore the principal object of my invention to provide means for limiting the movement of one of the heads so that the tensions of the opposite heads of the drum may be varied and controlled, and although the improvement of the present invention is especially adapted for drums in which the heads are adjusted simultaneously, it will be apparent that the improvement may be used with advantage in connection with other forms of drums. A particular object of the invention is to provide adjustable controlling means for use in a drum in which the heads are adjusted simultaneously whereby the movement of one of the heads, such as the snare head, may be limited or controlled after a predetermined movement thereof while permitting a continued operation of the adjusting means for effecting a further tightening of the other head of the drum.

The nature of my improvement, the means by which it is carried out, and the various objects of this invention, will appear more clearly from the following specification taken in connection with the accompanying drawings in which certain forms of my invention are illustrated.

In the drawings—

Figure 1 shows a perspective view of a snare drum embodying the features of the present invention;

Fig. 2 is a sectional view taken through the drum illustrated in Fig. 1, showing the construction and operation of my improvement;

Fig. 3 is a longitudinal sectional view of the construction illustrated in Fig. 2; and

Fig. 4 is a sectional view similar to that shown in Fig. 2, illustrating a modified form of my invention.

This improved drum comprises a cylindrical shell 10 having mounted on the ends thereof, the snare head 11 and the beater head 12, which have their edges wrapped around and secured to the flesh hoops 13 and 14 respectively. These flesh hoops 13 and 14 fit over the shell 10, and the movement thereof inwardly from the ends of the shell causes the heads of the drum to be tightened. The adjustment of the heads, by means of the flesh hoops, is effected through the hoops 15 and 16 which also fit over the drum shell in the same manner and engage the flesh hoops 13 and 14, respectively. The hoops 15 and 16 are engaged at a plurality of points around the drum by the hook members 17 and 18 having the hooks 17^a and 18^a which engage the hoops 15 and 16 respectively, so that when the hook members are drawn toward each other, the corresponding inward movement of the hoops 15 and 16 will operate to increase the tension of the drum heads. The hook members 17 are provided with longitudinal bores or apertures adapted to be rotatably engaged by the adjusting members or screws 20, having finger holds 21. The threaded portions 20^a of the adjusting members 20 have threaded engagement with longitudinally extending threaded apertures formed in the other hook members 18. The rotation of the adjusting members, by means of the finger holds, causes the two hoops 15 and 16 to be moved simultaneously toward each other in order to increase the tension of the drum heads.

It will be seen that the finger holds 21 are located, according to the better practice, adjacent to the snare head of the drum, so that they do not interfere with the operation of 5 playing the drum.

In order to get the best effect from a drum in the playing thereof, it is desirable that the beater head be adjusted to a tension equal to or greater than that of the snare 10 head, and in order to accomplish this, I have provided means for limiting, at any desired point, the movement of the snare head, which tends to stretch and tighten more readily than the beater head, so that 15 the continued operation of the adjusting means will thereafter serve to increase the tension of the beater head without effecting the tension of the snare head. In the form of my invention shown in Figs. 1 and 2, 20 this adjusting means comprises a series of studs, or lugs, 25 secured to the shell 10 around the central portion thereof, each lug 25 having a lateral cylindrical extension 26, and the parts 25 and 26 of each lug are 25 provided with central bores, or apertures, adapted to receive one of the adjusting screws 20 and form a bearing therefor. Each of the parts 26 is threaded on its outer side, as shown at 26^a, and is engaged 30 by an adjusting nut 27 having an outer knurled surface 27^a adapted to be engaged by the fingers of the operator. These adjusting nuts 27 may be moved to any desired position on the parts 26 and be caused 35 to engage the flesh hoop 13 of the snare head when the latter has moved to a predetermined point, so that further movement of the flesh hoop 13, or the hoop 15, will be prevented, and thereafter the continued operation of the adjusting members 20 will 40 serve to increase the tension of the beater head without affecting the tension of the snare head.

Instead of using the form of regulating 45 or adjusting means shown in Figs. 1 and 2, I may use the form shown in Fig. 4, which may be used with particular advantage on large drums, and in which the adjusting means is mounted independently of the 50 means for adjusting the tension of the heads of the drum. This latter form of the invention comprises a plurality of lugs, or studs, 30 secured to the shell 10 by means of screws 31 and threadedly engaged by screw members 32 having knurled heads 33 whereby 55 said screw members may be caused to engage the flesh hoop 13 in the manner previously described.

By means of this invention the relative 60 tensions of the opposite heads of the drum may be regulated and controlled in any desired manner while employing adjusting means which tightens both heads simultaneously. After the heads have been adjusted 65 in the desired manner, they may be relaxed,

then upon retightening them they will automatically assume the same relative tensions owing to the operation of the adjustable stops.

The snares 35 of the drum in the embodiment shown in the drawings are engaged by clamping means 36, which may be adjusted by means of the screw member 37 which is threaded through said clamping means, said screw member passing through a stud 38 70 on the hoop 16 at one end, and pivotally engaging within a stud 39 on the hoop 15 at its other end, whereby the tension of the snares may be regulated. This adjusting means for the snares of the drum, however, constitutes no part of the present invention. 75

Although I have shown and described certain embodiments of the invention for purposes of illustration, it will be understood that it may be constructed in various other 80 forms without departing from the spirit of my invention as defined in the appended claims. 85

What I claim is:

1. In combination, a drum shell, drum 90 heads mounted on said shell, hoops engaging said heads, means for drawing said hoops toward each other simultaneously, and means mounted between said hoops for arresting the movement of one of said hoops 95 while permitting said first mentioned means to cause continued movement of the other hoop.

2. In combination, a drum shell, drum heads mounted on said shell, hoops engaging said heads, clamping means engaging said hoops and having means for adjusting the tension of said heads, and means acting independently of the adjusting means and lying in the path of movement of one of 10 said hoops outwardly of said shell for controlling the movement of said hoop independently of the other.

3. In combination, a drum shell, drum heads mounted on said shell, hoops engaging said heads, clamping means engaging said hoops and having means for adjusting the tension of said heads, and means coöperating with said clamping means around the outer peripheral surface of the drum for 11 limiting the movement of one of said hoops.

4. In combination, a drum shell, drum heads mounted on said drum shell, hoops engaging said drum heads, clamping means engaging said hoops and having means for 12 adjusting the tension of both of said heads simultaneously, and adjustable means mounted independently of said hoops for controlling the adjustment of one of said heads independently of the other.

5. In combination, a drum shell, drum heads mounted on said drum shell, hoops engaging said drum heads, clamping means engaging said hoops and having means for adjusting the tension of both of said heads 13.

simultaneously, and adjustable means carried by said shell for controlling the adjustment of one of said heads.

6. In combination, a drum shell, drum heads mounted on said shell, hoops engaging said drum heads, clamping means engaging said hoops, operating members engaging said clamping means for adjusting said clamping means toward each other, lugs engaged by said operating members and attached to said shell, and adjustable means carried by said lugs to limit the movement of one of said hoops and permit the continued movement of the other hoop after a predetermined operation of said operating members.

7. In combination, a drum shell, drum heads having flesh hoops engaging said shell, hoops engaging the outer ends of said flesh hoops, two series of hook members engaging said second-named hoops, operating members rotatably engaging the hook members of one series and threadedly engaging the hook members of the other series, said operating members having finger holds adjacent one of said members of the drum, lugs attached to the shell of said drum, and stop members threadedly engaging said lugs and positioned to engage one of said flesh hoops for limiting the movement thereof upon operation of said operating members.

8. In combination, a drum shell, drum

heads mounted on said drum shell, hoops engaging said heads, clamping means engaging said hoops and having means for adjusting the tension of said heads, studs secured to said shell around the outer periphery thereof between said hoops, and adjustable members engaging said studs for controlling the movement of one of said hoops independently of the other.

9. In combination, a drum shell, drum heads mounted on said shell, hoops operatively connected to said heads and surrounding said shell, means for drawing said hoops toward each other simultaneously, and means for holding said first-named means adjacent said shell but operated independently of said first-named means for arresting the movement of one of said hoops while permitting said first-named means to cause continued movement of the other hoop.

10. In combination, a drum shell, drum heads mounted on said shell, flesh hoops connected to said drum heads and surrounding said shell, means for drawing said flesh hoops toward each other simultaneously, and means for engaging one of said flesh hoops to arrest the movement thereof while permitting said first-named means to cause continued movement of the other flesh hoop.

In testimony whereof I have subscribed my name.

TOM WILSON.
